HEATING SYSTEM

Joseph T. Norman, Huntington Mills, Pa.

Application September 22, 1948, Serial No. 50,571

5 Claims. (Cl. 237—67)

1

My invention relates to systems for heating buildings, and it particularly has for its object to utilize to the fullest extent the heat from furnaces now lost by passing the smoke and gases from the furnace directly into the chimney flue.

Further, the invention has for its object to increase the efficiency of present-day heating systems so as to obtain a greater percentage of heat from a given amount of heat-producing material (coal, for example) than it is possible to obtain with the present-day heating practice.

Again, it is an object to provide a heating system in which the smoke is consumed and sparks extinguished before the remaining products of combustion are released to the stack.

Again, it is an object to provide a heating system in the nature of an attachment to ordinary furnaces which also embodies provisions for connecting the smoke outlet of the furnace directly with the stack by a reduced area duct when the auxiliary apparatus is not working so as to maintain a low fire in the furnace ready for instant use when the auxiliary apparatus is called into action.

Further, the invention has for its object to provide an apparatus as an auxiliary which can be employed with furnaces that burn coal under natural draft, furnaces that burn coal under forced draft, or furnaces that burn oil or gas, without the necessity of changing the furnace structure, and which will operate in cooperation with the blower or the burner (as the case may be) thermostat controls now commonly employed.

Other objects will in part be obvious and in part be pointed out hereinafter.

To the attainment of the aforesaid objects and ends the invention still further resides in the novel details of construction, combination and arrangement of parts, all of which will be first fully described in the following detailed description, and then be particularly pointed out in the appended claims, reference being had to the accompanying drawings, in which:

Fig. 1 is a part vertical section and part elevation, somewhat diagrammatic in form, disclosing one embodiment of the invention.

Fig. 2 is a horizontal section on line 2—2 of Fig. 1.

Fig. 3 is a view similar to Fig. 1, but showing another embodiment of the invention.

In the drawings, in which like numerals and letters of reference designate like parts, in all the figures, 1 or 1^a represents the furnace. This furnace may be of any known construction,

2

either coal, burning under natural draft, coal, burning under forced draft as when stokers are used, oil burning or gas burning, as the case may be. For convenience of illustration I have shown a coal-burning natural-draft furnace in the first embodiment and an oil-burning furnace in the second embodiment of the invention.

The first embodiment

By reference to Figs. 1 and 2 it will be seen that 1 designates the furnace, 2 the grate, 3 the fire box, 4 the smoke flues within the furnace which lead to the outlet 5 that normally is of relatively large cross-sectional area and connects directly to a stack having a flue of like cross-sectional area for good natural draft.

The water and/or steam chamber of the furnace is indicated by 6 and the usual riser to the usual radiators (not shown) is indicated by 7. When my invention is used it is not necessary to have a stack of as large a cross-section as heretofore, for reasons which will be obvious later.

In applying my invention to existing heating plants, the smoke outlet of the furnace is capped at 8, to which cap is connected a pipe section 29 of a reduced cross-sectional area which joins with a pipe 28 within a casing 9, the pipe having a foraminous portion 33 immersed in water in the casing 9. A branch 30 adjacent the furnace leads into a pipe 27 that connects directly with the chimney flue (not shown). The outlet of this branch 30 is controlled by an automatically actuated valve 31 which is slightly overbalanced by a weight 32 on a pivoted valve carrying arm, of which more will be said later.

The casing 9 encloses a combined water and steam or vapor chamber 10 which is separated from a water-level control and condensate return chamber 11 by a suitable partition 15.

On the casing 9 is mounted a casing 16 for reception of the cooled and washed gases before they are passed to the chimney flue. The casing 16 is divided into two chambers 16^a and 41 by a partition 17, the chambers communicating at a high level and at a low level through suitable openings in the partition 17, as shown in Fig. 1.

The chamber 41 serves to receive the condensate from the radiators R.

The chamber 41 communicates with the chamber 11 through a port 18 normally closed by a valve 19 but which, when a determined amount of condensate accumulates in casing 16, is opened by the float 21 and lever 20 arrangement, shown

in Fig. 1. Chamber 41 communicates with chamber 16^x via a port 17^x.

Water is maintained at a constant level in chambers 10 and 11 (which communicate via a port 15^x) by means of an outlet valve 12 controlled by a float 13 similar to the float 20. The chambers 10 and 11 may be drained when desired via a suitable cock 14.

The centrifugal pump or blower 23 is mounted on casing 16 and has its inlet connected by a pipe or duct 25 with the interior of the casing 16, a baffle 22 being provided to prevent liquid from being sucked up.

The outlet 26 of the blower 23 connects to the pipe 27 above the outlet of branch 30 and valve 31.

24 designates an electric motor for operating the pump or blower 23. In practice the motor 24 will be thermostatically controlled, in any well known manner, to operate within certain room-temperature limits.

34, 35, 36 designate a number of auxiliary radiators R connected in series by pipes 38 and 39. A pipe 37 connects the first radiator 34 of the series with the steam or vapor space within casing 9, while a return pipe 40 connects the last radiator 36 of the series with the chamber 41.

The operation of the first embodiment of the invention is as follows: When motor 24 is not running, weight 32 holds valve 31 open and the chimney draft is then sufficient to keep a low fire in the fire box of the furnace. Now when motor 24 is energized and operates blower 23, the pressure set up in pipes 26 and 27, together with the suction set up in pipe 29-30, immediately closes valve 31 over the outlet of 30, so that all the products of combustion are drawn from the furnace outlet 5 through pipes 29, 28, 33 through the water in casing 9, pipe 37, the series of radiators R, pipe 40, casing 16 to blower 23 and from thence are forced through pipes 26 and 27 to the stack.

The hot gases drawn from the furnace in passing through the water in the chamber of casing 9 are not only washed, but these gases give off their heat to the water, causing it to vaporize and/or boil to form steam. This vapor and/or steam passing through the radiators R gives off heat to the atmosphere surrounding the radiators. The radiators may be placed at, above, or even below the furnace level, as desired, since the flow of fluid through the radiators is effected by the positive action of the centrifugal blower or pump 23.

As soon as the pump 23 stops, circulation from pipe 29 to pump 23 stops, pressure in pipe 26 drops to atmospheric, and chimney draft opens valve 31, causing sufficient natural draft from 5 via 30 to keep the fire alive until pump 23 starts up again.

If desired, a spark-arresting screen 55 may be inserted in pipe 27 to prevent sparks going into the chimney at any time, thus eliminating chimney fires, when direct or natural draft is acting.

Since the gases passing through the water and vapors in casing 9 take up moisture-carrying oxygen in passing through casing 9, a portion of the gases after leaving pump 23 may be passed by a pipe 56 (controlled by a valve 57) to the ash-pit of the furnace to assist draft and combustion in the furnace.

The second embodiment

In this embodiment of the invention (see Fig. 3) those parts which are of substantially the

same construction as corresponding parts in Figs. 1 and 2 bear the same reference number plus the index letter a, so a repetition of the description thereof is thought to be unnecessary.

This embodiment differs from the first embodiment in that the products of combustion are not washed in casing 9^a, but, after losing their heat to the water in such casing, they are passed to pipe 27^a for discharge to the chimney (not shown).

In this form of the invention the pipe 28^a leads to a coil or zig-zag pipe 42 that in turn connects with pipe 25^a, the pipe 42 always being immersed in the water.

Thus, steam is generated in casing 9^a. This steam is passed into a main riser 44 from which branch risers 47 carry it to the radiators 46 and from which return pipes connect with a main return pipe 45 by means of branches 48, suitable radiator control valves 49 being employed.

The casing 9^a may be provided with a water level glass 59, a steam pressure gauge 58 and a safety valve 59 of any approved construction.

I prefer to cover the pipes 28, 29, 30 (or 28^a, 29^a, 30^a) from collar 8 (or 8^a) to the casing 9 (or 9^a) with suitable heat insulation 43 so as to conserve the heat until released inside the casing.

In Fig. 3 the fire pot of the furnace is indicated by 51, the fuel burner by 52, fuel line by 54 and the fuel feeder by 53, all of which may be of any usual construction and per se constitute no part of the present invention.

From the foregoing description, taken in connection with the accompanying drawing, it is thought that the construction, operation and advantages of the invention will be clear to those skilled in the art, and I desire it understood that changes in the details of construction and arrangement of parts may be made without departing from the spirit of the invention and the scope of the appended claims.

What I claim is:

1. In combination with a furnace having a smoke outlet, of an auxiliary apparatus comprising a casing containing water, a pump, a pipe connection from said smoke outlet to said casing, a pipe connection from said casing to said pump, a pipe connection from said pump to a chimney connection, a pipe connection between said first mentioned pipe connection and said chimney connection and an automatic valve controlling passage through said last named pipe connection, said valve being constructed to open while said pump is at rest and to be closed when said pump is in action by the pressure differential generated adjacent the valve by the moving gases, said first mentioned pipe connection including a section extending into said casing below the water level and delivering the products of combustion into the water, said casing including a steam chamber and a return chamber, said second mentioned pipe connection leading from said return chamber to the pump, a set of serially connected radiators connected to said steam and return chambers respectively, and means to maintain water at a predetermined level in said steam chamber.

2. In combination with a furnace having a smoke outlet, of an auxiliary apparatus comprising a casing containing water, a pump, a pipe connection from said smoke outlet to said casing, a pipe connection from said casing to said pump, a pipe connection from said pump to a chimney connection, a pipe connection between said first mentioned pipe connection and said chimney

connection and an automatic valve controlling passage through said last named pipe connection, said valve being constructed to open while said pump is at rest and to be closed when said pump is in action by the pressure differential generated adjacent the valve by the moving gases, said first mentioned pipe connection including a section extending into said casing below the water level and delivering the products of combustion into the water, said casing including a steam chamber and a return chamber, said second mentioned pipe connection leading from said return chamber to the pump, a set of serially connected radiators connected to said steam and return chambers respectively, means to maintain water at a predetermined level in said steam chamber, and a float-valve-controlled port between said return chamber and said steam chamber.

3. In a heating system, a furnace having a smoke outlet and a jacket for heating fluid, a connection leading from said jacket for conducting heating fluid to radiators, at least one additional radiator, means for connecting said additional radiator to a chimney, and means for conducting the products of combustion from said smoke outlet to said additional radiator for passage through the same, and a direct connection between said smoke outlet and the chimney including an automatic balanced back check valve, and a forced draft creating means in said connection between said additional radiator and the chimney, said check valve being positioned below the place where said connection between said additional radiator and the chimney enters the chimney.

4. In combination with a furnace having a smoke outlet, a casing comprising a water containing chamber and a return chamber, a conduit connecting said smoke outlet with said casing, said conduit having a foraminous end terminating beneath the water level in said water chamber for delivering products of combustion, a pipe connected to said conduit and a chimney construction, an automatic valve interposed in said pipe and controlling communication with

said smoke outlet and chimney, a pump connected to said return chamber and communicating with said chimney, a pipe connected to said water chamber adjacent the top thereof for receiving steam and products of combustion, a series of radiators connected to the last mentioned pipe and communicating with said return chamber for delivering steam and products of combustion to said return chamber.

5. In combination with a furnace having a smoke outlet, a casing comprising a water containing chamber and a return chamber, a conduit connecting said smoke outlet with said casing, said conduit having a foraminous end terminating beneath the water level in said water chamber for delivering products of combustion, a pipe connected to said conduit and a chimney construction, an automatic valve interposed in said pipe and controlling communication with said smoke outlet and chimney, a pump connected to said return chamber and communicating with said chimney, a pipe connected to said water chamber adjacent the top thereof for receiving steam and products of combustion, a series of radiators connected to the last mentioned pipe and communicating with said return chamber for delivering steam and products of combustion to said return chamber, and a valve controlled pipe connected to the outlet side of said pump and to the furnace ash pit.
